UNITED STATES PATENT OFFICE.

EMIL F. W. SCHOENAUER, OF CHICAGO, ILLINOIS.

DIVING APPARATUS.

SPECIFICATION forming part of Letters Patent No. 614,626, dated November 22, 1898.

Application filed October 16, 1897. Serial No. 655,460. (No model.)

To all whom it may concern:

Be it known that I, EMIL F. W. SCHOENAUER, of Chicago, in the county of Cook and State of Illinois, have invented certain new and useful Improvements in Diving Apparatus; and I do hereby declare that the following is a full, clear, and exact description thereof, reference being had to the accompanying drawings, and to the letters of reference 10 marked thereon, which form a part of this specification.

This invention relates to improvements in diving apparatus, and refers more specifically to a closed shell or housing, commonly called 15 a "diving-bell," which may be sunk to the bottom of a body of water and which is provided with tool-actuating devices which are operable from the inside of the shell, by which a person inside of the shell may operate upon 20 vessels or other bodies exterior to the shell.

The invention consists in the matters hereinafter set forth, and more particularly pointed out in the claims.

In the accompanying drawings, Figure 1 is 25 a side elevation of a diving apparatus embodying my invention. Fig. 2 is a plan section taken on the indirect line 2 2 of Fig. 1. Fig. 3 is a side elevation of one of the disks in which the tool-actuating levers are mounted. Fig. 4 is an edge elevation thereof. Fig. 30 5 is a detail of one of the tool-actuating levers. Fig. 6 is a vertical section of an apparatus, taken on line 6 6 of Fig. 1. Fig. 7 is a longitudinal sectional view of the bolt-inserting 35 devices, taken on line 7 7 of Fig. 6. Figs. 8 and 9 are detail sections taken on lines 8 8 and 9 9, respectively, of Fig. 7. Fig. 10 is a detail sectional view of the outer end of the bolt-inserting devices, showing the clamping 40 jaws mounted therein. Fig. 11 is an end elevation of the parts shown in Fig. 10. Figs. 12 and 13 are cross-sectional views taken on lines 12 12 and 13 13 of Fig. 10. Fig. 14 is a perspective view of the chuck. Fig. 15 is a 45 perspective view of one of said jaws removed.

A diving apparatus embracing my invention consists generally of a housing A, which, as shown, is cylindric in form and made up of an outer shell A' and an inner shell A², 50 concentric with said outer shell. Said inner and outer shells are composed of a plurality of sheets of metal riveted together at their

edges. The inner shell is of considerable less diameter than the outer shell and is separated therefrom by means of distance-bars consisting of I-beams A³, placed vertically between said inner and outer shells and secured thereto by rivets a', passing through the flanges thereof and through said shells. Within the inner shell are located heavy horizontal 55 strengthening rings or ribs A¹³, which are attached to the said inner shell. Said rings or ribs serve to support the said I-beams from being thrust or crushed inwardly by outside pressure on the walls of the chamber. Any 60 desired number of such rings may be used, two only being shown in the drawings. This construction affords great strength in the housing A and capacity to resist the pressure of the water through which it is sunk, while 65 at the same time giving lightness to the structure as a whole. The housing is provided with upper and lower walls A⁴, which in this instance are of convex form on their outer 70 surfaces. Said walls consist of two thicknesses of sheet metal A⁵ A⁶, which are separated from each other and secured rigidly together by means of curved I-beams A⁷, which are arranged radially and attached at their 75 ends to the I-beams A³. The outer thickness 80 of the upper wall is provided on its outer margin with an annular flat flange A⁸, which is perpendicular to the vertical walls of the housing, and the upper end of the outer shell A' of the housing is provided with a radially- 85 extending annular flange A⁹, which in this instance consists of a separate curved angle-bar secured to said upper edge of the shell by means of rivets a². Said annular flange A⁹ is 90 equal in diameter to the diameter of the outer thickness of the upper wall, rests in contact with the horizontal annular surface A⁸, and is secured thereto by means of bolts or rivets a³. The inner thickness of said upper wall is 95 provided with an annular vertically-extending flange A¹⁰, which extends downwardly within and is secured to the upper edge of the inner shell A² of the housing by means of rivets a⁴. The lower wall A⁴ of the housing is 100 made like the upper wall just described, with the exception that the outer thickness A⁵ is secured to the lower edge of the outer shell A' by being provided with an upwardly-extending flange A¹¹, which fits within and is se-

cured to the lower edge of said inner shell by means of rivets a^5 . With the exception just noted the parts of the lower wall are lettered like those of the upper wall described.

5 The apparatus will be provided with supply and return air-pipes B B' , which are shown as inserted through the upper wall thereof to maintain a supply of air within the chamber. Suitable ballast will be provided in the bottom of the chamber, which is herein shown as consisting of block C of iron or the like, placed beneath a flooring C' in the bottom of the housing. Said housing is provided with a plurality of windows or outlooks D , which 10 consist of metal frames D' , bolted to the inner and outer shells of the wall. As herein shown, D' designates a rectangular plate or frame which is mounted in and closely fits within openings in the inner and outer shells A' and A^2 , the opening in the inner shell being smaller than that in the outer shell. Said frame is provided with a marginal flange d , through which bolts or rivets d' pass, by 15 means of which said plate is rigidly secured to said outer shell A' . Said plate D' is provided with a flaring opening which is wider at its outer than its inner end and which is herein shown as of rectangular form. The frame D' extends at its inner side into contact with the outer face of the inner shell A^2 , around the opening in the latter, and a clamping frame or ring D^2 is applied to the inner 20 face of said inner shell opposite said plate, said ring D^2 being provided with an opening similar in shape to and of the same size as the opening of said outer plate D' . The said frames D' and D^2 are held together by bolts d^2 , which pass through the inner shell and serve to rigidly join said parts. In a groove 25 formed between said inner and outer frames D' and D^2 and covering the opening therein is mounted a heavy plate-glass D^3 , which gives access of light to the interior of the chamber. Said glass being located at the inner part of the opening and at a distance from the outer face of the inclosure is protected 30 from injury by objects which may come in contact with the inclosure. The housing may be provided with any number of such windows as is found desirable. To close the windows 35 in case of breakage of the glass, safety-covers D^4 are provided, the same being pivoted to the frames at the top or bottom of the windows and provided with securing devices for 40 holding them securely closed.

55 As a means of gaining access to the interior of the chamber the same is provided in one of its walls with a manhole E , which is constructed as follows: The inner and outer shells 60 of the housing are provided with oppositely-arranged openings E' E^2 , the latter of which is of greater diameter than the former.

65 E^3 designates a cast-metal frame which is mounted in the opening E^2 of the outer shell A' , with its inner face in contact with the inner shell A^2 , and is provided on its outer face with a flat flange E^4 , which rests against the

outer face of the shell A' , outside of the opening therein, and is secured to said outer shell by means of bolts e , which pass through the 70 same through said shell. Said frame E^3 is provided also on its inner side with a rabbet E^5 of a depth approximately equal to the thickness of the inner shell and within which fits the margin of the shell around the opening E' 75 therein. Said frame E^3 is secured to the inner shell by means of tap-bolts e' , which pass through a clamping-ring E^6 on the inner face of said inner shell and through said inner shell into the frame. Said clamping-ring E^6 80 is provided with an opening approximately equal in size to the central opening of the frame E^3 , both openings being preferably of oblong form. The opening in said frame is of outwardly-flaring form, being greater in size 85 at the outer than at the inner face thereof. Said frame E^3 serves to rigidly secure the inner and outer shells together around the openings therein.

90 E^7 designates a manhole-cover which fits against the flange E^4 of the frame E^3 and is provided with an inwardly-extending flange E^8 , which fits within the conically-shaped interior surface of the frame and is preferably as deep as the thickness of said frame. In 95 order to provide a water-tight joint between said cover and the frame E^6 , a packing or gasket E^9 , of any suitable material, such as rubber, is interposed between the said parts. Said cover E^7 is adapted to be tightly clamped 100 against the packing-ring, and this is accomplished in the present instance by means of two coacting bolts E^{10} and E^{11} . The bolt E^{10} is inserted through a central opening in the plate and has screw-threaded engagement at 105 its inner end with the bolt E^{11} , which latter passes through a central opening in a spider E^{12} , arranged to bear against the inner face of the clamping-ring E^6 . As herein shown, the bolt E^{10} is provided with a screw-threaded 110 axial aperture, and the end of the bolt E^{11} is made of such size as to fit within said aperture, so that when either bolt is tightened the cover may be rigidly clamped upon the frame 115 E^3 and a water-tight joint secured. With this construction it will be seen that the manhole-cover E^7 may be removed and clamped in place either from the inner or outer side thereof, as it may become necessary.

120 Suitable tool-actuating devices are mounted in the walls of the chamber, to the outer ends of which are adapted to be attached different tools, which are actuated from the inside of the housing. As herein shown, said housing is provided at adjacent points in the lower 125 part of its side wall with two oscillatory tool-operating levers F , which are provided on their inner ends with operating-handles f , by means of which they may be actuated. Said levers are pivoted between their ends in the 130 wall of said housing by means permitting them to be oscillated in any plane desired. The said levers are alike in their construction, and in the following description but one will

be referred to. The construction by which the oscillatory movement of the levers in different planes is accomplished is as follows: The inner and outer shells A' A² of the walls 5 of the housing are provided with concentric openings f' f², the latter of which is of greater diameter than the former, and within said openings is mounted a two-part open frame or ring, which consists of an outer portion F', 10 equal in diameter to the diameter of said opening f² and mounted therein, with its inner side engaging the inner shell A² of the wall. Said outer portion F' of the ring is provided on its outer side with a flange f³, which rests 15 against the outer face of the shell A' and is secured thereto by means of bolts f⁴ passing therethrough and through said shell. Said outer portion of the ring is provided with a central circular opening, which is of conical 20 or flaring shape at its outer part, as seen in Fig. 2 of the drawings. The inner portion F² of the ring is of less thickness than the outer portion thereof and is provided with an inwardly-flaring or conical-shaped central aperture, which registers with the aperture f' 25 of the outer part of the ring. Said inner portion of the ring is secured in place and in rigid relation with the outer portion thereof by means of tap-bolts f⁵, which pass through 30 the inner shell A² and into the outer portion F' of the ring. Said outer portion F' of the ring is provided with an annular recess or rabbet F³, which lies in a plane perpendicular to the central axis of the ring and concentric 35 therewith and forms with the inner portion F² of the frame an annular groove. Within said groove is mounted a disk F⁴, in which the oscillatory lever F is pivoted. Said disk is mounted within the recess, so as to have a 40 free rotary movement therein about its axis of rotation. In order that the lever may be pivotally mounted in the disk in a manner to permit its removal therefrom, said disk is herein shown as made of two parts, being di- 45 vided in the plane of the pivot of the lever and provided in its adjacent parallel faces with bearing-apertures f⁶, within which the ends of the pivot-shaft f⁷ enter. Said disk is thickened in its central part, as shown at f⁸, 50 to provide additional strength where it is engaged by the pivot-pin of the lever F. The adjacent faces of the disk are cut away to provide a part-cylindric recess F⁵, adapted to receive a cylindric block F⁶, forming a part of 55 the said lever F, said block being arranged to fit closely within the recess and to form therewith a water-tight joint to prevent ingress of water to the interior of the chamber. In order to further prevent the passage of the 60 water between the said cylindric block and the adjacent parts of the disk, said disk is provided at the opposite edges of said block with packing-grooves, within which are mounted suitable packings f⁹, as shown more 65 clearly in Figs. 2 and 4. With this construction it will be seen that the plane of oscillation of the lever may be changed as the re-

quirements of the work dictate, it being obvious that by rotating the bearing-disk F⁴ in its bearing-groove the plane of oscillation of 70 said lever may be changed as desired. Said lever may be removed from its bearings by first removing the inner portion F² of the frame, after which the lever and disk may be pulled inwardly until said disk is released 75 from the rabbet F³, when the parts of the disk may be separated and removed from the lever. The insertion of said disk in place will of course be merely a reversal of this operation. The flaring or conical shape of the opening of 80 the frame or bearing-ring on the inner and outer side thereof provides ample room for the oscillation of the lever to any desired angle, as clearly seen in Fig. 2. Said lever F will in practice preferably be made in three 85 parts—namely, a central or bearing part f¹⁰, upon which the cylindric block is formed, an outer arm or part f¹¹, to which the tool is fastened, and the inner portion or hand-lever f. Said part f¹¹ will be made so as to be readily detached from the middle or bearing portion of the lever, so that it may be easily removed and an arm of a different shape or character substituted, it being understood 90 that different tools and different operations may require external arms of different shapes, lengths, or sizes. For some purposes it may be necessary to clamp or hold the disk F⁴ from turning in the housing, and this may be accomplished by means of a set-screw F¹², inserted through the inner portion of the frame 95 and bearing against the said disk.

The levers F being capable of rotation in the housing may be used for drilling or like operations, it being obviously practicable to 100 attach a boring-tool or the like to the outer end of the lever and giving suitable rotary motion thereto.

As herein shown, the housing is provided at its upper part with a third oscillatory lever 110 G. Said lever is mounted in the wall of the housing and is in all respects similar to the levers just described. It is, however, shown as provided on its outer or operative end with a bent portion which stands at right angles 115 to the main body of the lever and upon the outer end of which is mounted a suitable clamping device G'.

The levers F and G may obviously be used either separately or together in performing 120 different operations—as, for instance, two of them may be used to operate a crosscut-saw by attaching the ends of such saw to adjacent levers, or two levers may be used to operate axes for chopping, the two levers in such case 125 operating at an angle to each other, so as to make converging cuts, such as are made by axmen in felling trees.

As a further and separate improvement the diving apparatus illustrated is provided with 130 means for inserting lag or other screws or for driving nails. Said device, like the oscillatory tool-actuating levers, is mounted with its operative end projecting through the wall

of the housing and with its inner end located within the chamber of the diving apparatus. Said device is constructed as follows:

H designates a chamber or cylinder, which is mounted in suitable openings in the inner and outer shells of the wall of the apparatus, so as to project at its opposite ends beyond both sides of said wall. Said cylinder is herein shown as secured to the opposite shells of the housing by means of angle L-shaped rings h, which are secured to the shells and to the chamber by rivets or bolts h'. Said cylinder H is closed at its ends by end walls H', and said walls are provided with circular apertures or openings concentric with the central axis of the cylinder. Within said cylinder is mounted a reciprocating and rotary hollow shaft H², which is of such external diameter as to fit closely within the opposite openings of the end walls H' of the cylinder. Said shaft is provided within the cylinder with guide-flanges H³, which are of such external diameter as to closely fit within the inner surface of the cylinder, there being preferably two of such flanges, one adjacent to each end of said cylinder. Said cylinder is made of two parts in order to fit over the shaft and is preferably united in longitudinal lines of contact. Between said guide-flanges and around the sleeve H² is placed a packing H⁴, which insures a water-tight joint between said shaft and cylinder. The hollow shaft is adapted to move endwise within the said cylinder, as well as turn freely therein, the guide-flanges being arranged at a distance apart considerably less than the length of said cylinder. Said shaft H² is open at its inner end and closed at its outer end by an end wall H⁵ and is provided in said end wall with an oblong opening h², as seen more clearly in Fig. 11.

H⁶ designates a driving-spindle, which is mounted in the hollow shaft H², with the inner end thereof projecting beyond the shaft inside of the chamber. Said spindle is adapted to carry at its outer end a chuck I, adapted to grasp and hold a bolt or lag-screw J or a nail which is to be driven into the hull of a sunken vessel or like place for making temporary repairs, and thereby enabling the water to be pumped out and the vessel to be raised. In case of a steel-clad vessel and where a leak is to be repaired by securing a sheet of steel over the broken part of the hull I intend to employ in connection with said chuck a threaded bolt or screw J of special and novel construction, by which said plate may be secured in place. Said screw or bolt is shown more clearly in Fig. 10 and is shaped to form a drill, by which a hole will be bored in the steel, and a tap to cut the thread by which it is to be held therein. As herein shown, said screw or bolt consists of a drill-point j, which, when to be used in metal, is made in the form of a metal drill-bit, a screw-threaded portion j', which is made of such hardness as to cut the threads in the hole

made by the drill j, a shank j², and a head j³. In order that said screw may be grasped by the chuck, it will be provided outside of the head with a square shank j⁴, by means of which it may be turned or driven. When this form of screw is to be used in wood, it will be understood that the construction will be similar to that described, with the exception that the outer end thereof will be made in the form of a boring-bit and the threaded part will have threads of the kind usual in wood-screws.

The chuck is shown in detail in Figs. 10 to 14, inclusive, and is made as follows: The inner end of the spindle H⁶ is provided with a short axial recess or bore H⁷, which is internally screw-threaded, as seen more clearly in Fig. 10. In the bottom of said recess and parallel with the central axis of the shaft is mounted a conical plug H⁸, which will preferably have screw-threaded connection with the shaft and arranged with its conical portion projecting centrally into said recess. I' I² designate chuck-jaws, which are mounted in the recess H⁷ and have screw-threaded connection therewith. The screw-threaded portions of said chuck-jaws are formed on a slightly-inward taper, so that as they are moved inwardly into the recess by their screw-threaded connection with the shaft the outer ends thereof are brought together or closed with a clamping action. The inner ends of said chuck-jaws are formed obliquely with respect to the central axis of the recess H⁷, so as to engage the oblique surface of the conical plug H⁸. Moving said jaws inwardly upon the cone has the effect of bringing the outer ends of the jaws toward each other, and the said plug acts in connection with the outer tapered surfaces of the jaws to move the jaws bodily inward, and to thereby clamp the shank j⁴ of the bolt J, so as to firmly hold said bolt therein. Preferably the two opposite jaws I' only of the four jaws are extended outwardly through the oblong slot h² of the sleeve H², Figs. 7 and 10, while the jaws I² stop short of the end wall H⁵ of said sleeve. If found desirable, however, said jaws I² may also be made of such length as to extend beyond the sleeve H², in which case the slot h² will have the form of a Maltese cross. In order that said jaws may not drop out of their screw-threaded connection with the spindle H⁶ when the screw or bolt J has been removed therefrom, the main or body portions of said jaws will be made of segmental form in cross-section, so that when assembled, as shown in Fig. 14, they form an almost complete conical plug. Their construction will prevent parts from moving sufficiently within the aperture of the shaft to become disengaged from the screw-threads therein. It will be understood, of course, that sufficient clearance will be left between the adjacent oblique faces of the jaws to provide for the necessary clamping action thereof. Said shaft H² is shown as provided on its inner end with a driving-pul-

ley, by which the same and the spindle may be driven from any suitable source of power—such, for instance, as an electric motor. Obviously other driving means may be employed 5 for actuating the shaft and spindle—such, for instance, as a balance-wheel operated by hand. To provide means for feeding the spindle outwardly as the same is rotated, I have shown a bent lever K, which is mounted upon a 10 bracket or standard K', secured upon the inner wall of the chamber. One end of said lever K' is adapted to engage the extreme inner end of the spindle H⁶, while the other or operating end K' is adapted to be grasped by the hand to exert power upon the shaft in a 15 well-known manner.

By an inspection of Figs. 11 and 12 it will be noted that when the spindle H⁶ is within the hollow shaft H² and the chuck-jaws project 20 through the rectangular opening h² of said shaft said shaft and spindle will be held from movement with relation to each other, so that when the spindle is rotated to drive the combined drill and bolt into the work 25 the shaft H² will rotate within the cylinder H, the shaft and spindle forming, in effect, at this time a rotative driving-shaft. The rotative friction will therefore be between the shaft H² and cylinder H, and a lubricant will 30 be applied to said parts in any convenient manner. When it is desired to disengage the chuck-jaws from the shank of a bolt which has been driven home, this will be accomplished by holding the shaft H² from rotation 35 within the cylinder H and turning the spindle in a direction the reverse of that in which it is rotated when driving the bolt. Owing to the interlocking connection of the projecting chuck-jaws with the hollow shaft, as 40 above described, said shaft will hold the several jaws from movement, and the reverse rotation of the spindle will permit the chuck-jaws to expand, so as to disengage the same from the shank of the bolt. The shaft H² is 45 herein shown as provided with a handle H¹⁰, by which the same may be held from rotation when the chuck is being disengaged from the bolt in the manner described. In order to 50 more firmly connect the spindle with the hollow shaft, a clamping device may be employed, such as a set-screw h⁵, Fig. 7, which is inserted through the hollow shaft and bears at its inner end against the spindle.

The parts of the bolt-inserting devices are 55 so constructed and arranged that the spindle may be withdrawn through the hollow shaft H² after the bolt has been driven and another screw then engaged with the chuck, the parts being so constructed and arranged that when 60 the chuck has been disengaged from the screw, as above described, the spindle may be withdrawn through the shaft H² to the interior of the chamber and another bolt then engaged with the chuck for insertion into the 65 work, as before stated. For this purpose the spindle H⁶ is mounted so as to be longitudinally movable in the shaft H² and so as to be

capable of being completely withdrawn therefrom. In order that water may not enter through the shaft to the interior of the chamber when the spindle is withdrawn, the inner end of said shaft is provided with a sliding gate or valve L, which is shown in detail in Figs. 7 and 8. Said gate, as herein shown, 70 consists of a flat thin plate which is inserted 75 transversely into the sleeve through a suitable slot and is provided with a circular inner end to conform to the opposite inner curved wall of the shaft when in its closed position. Said shaft will be of such length in- 80 side of the slide gate or valve L that when the spindle is withdrawn to the inner end thereof there will be sufficient distance between the gate and the inner end of the sleeve to accommodate the full length of the bolt and at the 85 same time maintain the outer end of the spindle within the inner end of the shaft, so as to close the latter against ingress of water. This construction permits the gate or valve 90 to be closed before the spindle is completely withdrawn from the shaft, so that at no time during the withdrawal of said spindle will there be an opening through which water may enter to the interior of the apparatus. With 95 this construction it will be seen that the spindle may be withdrawn through the shaft as each bolt or nail is driven and a new one supplied to the chuck without danger of water flooding the apparatus and without the necessity of lifting the apparatus above the surface of the water. A packing h⁶ will be placed 100 in a suitable packing-groove in the spindle between said spindle and the interior of the shaft, herein shown as at the outer end thereof. It will be understood that in case nails 105 or spikes are used instead of bolts, as herein shown, said nails will be driven home by striking the inner end of the spindle with a hammer or other suitable tool. It will also be understood that the recharging of the 110 chuck as each nail is driven home will be in all respects like the operation hereinbefore described.

In the operation of the device the shell will be provided with suitable means by which 115 lifting-cables may be attached thereto. It will furthermore be understood that when a steel plate or board is being attached to the side of a vessel or the like by means of bolts inserted therethrough and into the said vessel 120 by the bolt-inserting device H the levers F and G may be employed to hold said plate or board in place. For this purpose said levers may be provided with suitable 125 grappling devices for grasping the plate or board.

I claim as my invention—

1. A diving apparatus comprising inner and outer parallel side walls or shells, vertically-arranged distance-bars interposed between 130 and secured at their opposite edges to said shells, inner and outer convex end walls secured to the ends of the side walls and radial curved distance-bars interposed between and

attached to said end walls, and attached at their outer ends to the said vertical bars.

2. A diving apparatus comprising inner and outer parallel side walls or shells, vertical distance-bars interposed between said walls or shells, and horizontal ribs or rings secured to the inner surface of the inner side wall or shell.

3. In a diving apparatus, the combination with the side walls thereof provided with a manhole, a manhole-cover, a spider engaging the inner face of said side walls and clamping means comprising a two-part bolt engaging said covering and spider and connected at their inner ends, said clamping means being operable from both the inside and outside of the apparatus.

4. In a diving apparatus, the combination of a side wall thereof provided with a manhole, a manhole-cover, a spider engaging the inner face of the wall, a telescopic clamping-bolt passing through said cover and engaging a part carried by said spider, and means for tightening and releasing said bolt from both the inside and outside of the apparatus.

5. In a diving apparatus, the combination of the side wall thereof provided with a manhole, a manhole-cover, a spider engaging the inner face of the wall, an outer clamping-screw passing through said cover, and an inner clamping-screw engaging the spider and having screw-threaded engagement at its end with the outer clamping-screw.

6. In a diving apparatus embracing inner and outer walls provided with oppositely-arranged openings, an apertured outer frame secured to said outer wall and provided at its inner side with a rabbet to receive the margin of said inner wall, and a clamping-ring bolted to the said frame by bolts which pass through said inner wall.

7. A diving apparatus embracing inner and outer walls provided with oppositely-arranged openings, a two-part frame consisting of an outer member which is attached to the outer wall and is in contact with said inner wall, an inner clamping member located in contact with the inner face of the inner wall, a plate of glass held at its edges between the inner and outer members of said frame, and clamping-bolts, which pass through the inner shell and hold together the said inner and outer members of the frame.

8. A diving apparatus comprising a water-tight chamber or compartment, provided with an opening in one of its walls, a disk rotatably mounted in said opening, and an oscillatory tool-actuating lever mounted in said disk and having angular movement with relation thereto.

9. A diving apparatus comprising a water-tight chamber or compartment provided with an opening in one of its walls, a disk rotatably mounted in said opening and provided with an elongated opening, and a tool-actuating lever pivotally mounted in said disk and provided with an integral cylindric block

which fills said opening and forms a water-tight joint with the disk.

10. A diving apparatus comprising a water-tight chamber or compartment provided with an opening in one of its walls, a two-part disk rotatably mounted in said opening, the members of said disk being provided in their adjacent edges with oppositely-arranged recesses which form an elongated opening therein, and a tool-actuating lever provided between its ends with a cylindric block which fills said opening in the disk.

11. In a diving apparatus comprising a water-tight chamber or compartment, provided with an opening in one of its walls, a two-part disk mounted in said wall, the adjacent faces of the members of the disk being provided with oppositely-arranged recesses which form an elongated opening and with bearing-apertures located in said recesses, a tool-actuating lever mounted in said disk and provided between its ends with a cylindric block which fills said opening of the disk and is provided with oppositely-arranged pivot-studs which engage said bearing-apertures of the disk.

12. In a diving apparatus comprising a water-tight chamber or compartment provided with an opening in one of its walls, a two-part ring mounted in said opening and provided with an annular bearing-groove, a disk having marginal engagement with said groove and adapted to rotate therein, said disk being provided with a central slot or opening, and a tool-actuating lever extending through said slot, said lever being provided with an integral cylindrical block which fills and turns in said slot.

13. A diving apparatus comprising a chamber having inner and outer walls provided with oppositely-arranged openings, a two-part bearing-ring, between the parts of which the inner wall is clamped, and the outer member of which is secured to the outer wall, a disk rotatably mounted in said bearing-ring, a tool-actuating lever passing through and pivotally mounted in said disk, and means affording a water-tight connection between said lever and disk.

14. A diving apparatus comprising a water-tight chamber or compartment and a bolt-inserting device embracing an outer endwise-movable hollow shaft which extends through the wall of the chamber and an inner spindle removably mounted therein and provided on its outer end with means for holding a bolt or the like, means operable from the inside of the chamber for disengaging the bolt from the spindle when the latter is at the outer limit of its movement and means for closing the opening through said shaft when the spindle is withdrawn therefrom.

15. A diving apparatus comprising a water-tight chamber or compartment and a bolt-inserting device embracing an outer endwise-movable hollow shaft which extends through the wall of the chamber, and an inner spindle removably mounted in said shaft and pro-

vided on its outer end with means for holding a bolt or the like, means operable from the inside of the chamber for disengaging the bolt from the spindle when the latter is 5 at the outer limit of its movement and a slide valve or gate in said sleeve for closing the same when the spindle is withdrawn.

16. A diving apparatus comprising a water-tight chamber or compartment, and a bolt-inserting device embracing a rotative and endwise-movable hollow shaft which extends through and has water-tight connection with the wall of the chamber, an inner spindle which passes through the hollow shaft and is 10 provided with bolt-holding means, and means for closing the opening through the shaft when the spindle is withdrawn therefrom.

17. A diving apparatus comprising a water-tight chamber or compartment, and a bolt-inserting device embracing a rotative and endwise-movable hollow shaft, a stationary cylinder in which said hollow shaft slides and turns, an inner spindle which passes through the hollow shaft and is provided with bolt-holding means, and means for closing the opening through the shaft when the spindle is withdrawn therefrom.

18. A diving apparatus comprising a water-tight chamber or compartment and a bolt-inserting device embracing an outer hollow shaft, an inner spindle provided in its outer end with a bolt-holding chuck having interlocking engagement with the shaft, means for actuating said bolt-holding means from within the chamber, and means for closing said hollow shaft when the spindle is withdrawn therefrom.

19. A diving apparatus comprising a water-tight chamber or compartment, and a bolt-inserting device embracing a rotative and endwise-movable hollow shaft which extends through and has water-tight connection with the wall of the chamber, an inner spindle which passes through the hollow shaft and is 45 provided with bolt-holding devices, means for actuating said bolt-holding devices from the interior of the chamber and means for closing the opening through the hollow shaft when the spindle is withdrawn therefrom.

20. A diving-bell comprising a water-tight chamber or compartment and a bolt-inserting device embracing an outer hollow shaft which extends through the wall of said chamber, and an inner spindle provided on its outer 55 end with a bolt-holding device adapted to insert a bolt when rotated in one direction and to release said bolt when the direction of rotation is reversed.

21. A bolt-inserting device embracing an outer rotary, endwise-movable, hollow shaft, an inner spindle removably mounted in said shaft and provided at its outer end with means for holding a bolt or the like, means for feeding the shaft to its work, and means 60 for closing said shaft when the spindle is withdrawn therefrom.

22. A bolt-inserting device embracing an outer, rotary, endwise-movable, hollow shaft, an inner spindle removably mounted in said shaft and provided at its outer end with means for holding a bolt or the like, means for closing the hollow shaft when the spindle is removed therefrom, and means for giving 70 rotary motion to the shaft and spindle.

23. A bolt-inserting device embracing an outer hollow shaft, an inner spindle removably mounted in said shaft and provided on its outer end with means for holding a bolt or the like, means for feeding the shaft and spindle to the work comprising a lever pivoted between its ends adjacent to one end of said spindle, provided with an operating-handle and adapted to engage the inner end of the spindle, and means for closing said shaft when the spindle is withdrawn therefrom. 85

24. A diving-bell comprising a water-tight chamber or compartment and a bolt-inserting device embracing a hollow endwise-movable shaft, which extends through the wall of said chamber and is connected therewith by means 90 affording water-tight connection, an inner rotative and removable spindle provided at its outer end with means for holding a bolt or the like, and a slide gate or valve in said shaft for closing the same when the spindle 95 is withdrawn therefrom, said valve being located from the inner end of the shaft a distance greater than the distance between the outer end of the bolt when attached to the spindle and the outer end of said spindle. 100

25. A diving-bell comprising a water-tight chamber or compartment and a bolt-inserting device embracing an outer hollow shaft which extends through the wall of said chamber, an inner spindle removably mounted therein, 105 said spindle being provided on its outer end with means for engaging and holding a bolt, and actuating connections between said holding means and the hollow shaft constructed to release said bolt by the turning of the 110 spindle in the shaft.

26. A bolt-inserting device embracing an outer stationary cylinder, a hollow shaft which rotates and slides endwise therein, a spindle removably mounted in said shaft and provided on its outer end with means for holding a bolt or the like, means for locking the shaft and spindle from relative rotation, means for turning the shaft and spindle, and means for closing the bore of the shaft when the spindle 120 is withdrawn therefrom. 115

27. A bolt-inserting device embracing an outer stationary cylinder provided with centrally-apertured ends, a hollow shaft having a cylindric enlargement which fits the cylinder 125 and has rotary and reciprocatory movement therein, a spindle removably mounted in said shaft and provided on its outer end with means for holding a bolt or the like, and means for closing the bore of the shaft when 130 the spindle is withdrawn therefrom.

28. A bolt-inserting device comprising an

- outer stationary cylinder, a hollow shaft mounted therein and provided with circular guide-flanges and with interposed packing-rings forming a cylindric enlargement to fit 5 the cylinder, a spindle mounted in said shaft provided on its outer end with means for holding a bolt or the like, and means for closing the bore of the shaft when the spindle is withdrawn therefrom.
- 10 29. A bolt-inserting device embracing an outer stationary cylinder, a hollow shaft having rotary and reciprocatory movement therein, a spindle removably mounted in said shaft and provided at its outer end with a chuck 15 for holding a bolt or the like, said chuck having jaws which extend beyond the end of the spindle, and the shaft having its outer end closed by a wall provided with an opening

which engages the clutch-jaws, whereby the latter may be actuated. 20

30. A diving apparatus comprising a water-tight chamber or compartment and a bolt-inserting device embracing an outer hollow shaft, an inner spindle, a bolt-holding chuck in the outer end of said spindle engaging an angular opening in the outer end of said shaft 25 and means for closing said hollow shaft when the spindle is withdrawn therefrom.

In testimony that I claim the foregoing as my invention I affix my signature, in presence of two witnesses, this 11th day of October, 30 A. D. 1897.

EMIL F. W. SCHOENNAUER.
